UNITED STATES PATENT OFFICE.

HENRY M. LANE, OF DETROIT, MICHIGAN.

CONVEYING MECHANISM.

1,340,962.

Specification of Letters Patent.

Patented May 25, 1920.

Application filed September 25, 1919. Serial No. 326,202.

To all whom it may concern:

Be it known that I, HENRY M. LANE, a citizen of the United States, residing at Detroit, in the county of Wayne and State of Michigan, have invented certain new and useful Improvements in Conveying Mechanism, of which the following is a specification.

This invention relates to conveying mechanism and it consists of an overhead trolley for use in foundries and other industrial plants, the trolley being adapted to travel upon an overhead track and being provided with suitable work supporting means, means 10 for elevating the work supporting means and traversing means for the trolley, an operator's cage carried by the trolley capable of vertical movement, the operator's cage being arranged to permit raising and lowering independent of the work supporting means; all as more fully hereinafter set forth and as claimed.

In conveying mechanism for industrial plants, it has been found advisable to employ overhead trolleys of the monorail type which travel over the heads of the workmen and thereby save space in the arrangement of the plant. In the first apparatus of this kind employed in industrial plants, the 20 trolley was not provided with propelling means, but was adapted to be pushed along the track by a workman from the floor. As an improvement, trolleys provided with traversing means have lately come into use 30 necessitating an operator's cage for controlling the movement of the trolley. In a prior Patent No. 1,266,828, patented May 21, 1918, I have described and claimed a conveying mechanism in which the work supporting 35 means and the operator's cage are supported in a framework and are vertically movable with respect to the trolley. The construction therein shown permits the operator to lower the work supporting means and his 40 cage for the purpose of releasing the load or allowing the operator to get out of the machine.

In the present invention I have devised an improvement over the apparatus shown in 45 my former patent. In this apparatus, I provide independent controlling means for the work supporting means and for the operator's cage. In the use of this machine it is possible for the operator to lower his cage 55 without lowering the work supporting means, and it is also possible to lower the

work holding means without lowering the operator's cage. It is advantageous to have the operator ride as close as possible to the ground even after the load carried by the 60 work supporting means has been elevated. With the present apparatus it is possible for the operator to fasten the load to the work supporting means, elevate it and operate the machine with the cage in the lowered position. As he approaches obstructions in his 65 path of travel he may raise the cage to avoid such obstructions and lower it again after passing. If it is necessary for the operator to leave the machine at any time without removing the load from the load supporting means, he may do so by merely lowering the cage.

In the accompanying drawing I have diagrammatically illustrated one embodiment 75 of this invention. In this showing, the view represents a side elevation of the trolley traveling upon a single track, part of the track and trolley frame being broken away.

Referring to the drawing, the letter A 80 represents a monorail track adapted to be placed in a building near the roof or ceiling. The trolley consists of a machine frame B provided with trolley frames C carrying trolley wheels D adapted to ride on the 85 flange E of the track. A motor F, diagrammatically illustrated, is arranged upon the trolley, and is connected to one of the trolley wheels by gearing, diagrammatically illustrated, as G.

As shown, the work supporting means 90 consists of one or more hooks H carried on cables I passing over guide rollers J. The supporting ropes are wound on drums K carried by brackets k and arranged on a 95 shaft connected by proper gearing to the motor L. The motor is supported from the frame in the machine by bracket l.

The operator's cage comprises a basket M mounted in vertical guides m and capable of 100 vertical adjustment. The basket is supported in the vertical guides by cables N which pass over guide rollers n. The cables are wound on drums O on a shaft connected by proper gearing to the shaft of a motor P 105 carried by bracket p.

The cage may be supported directly from the frame of the trolley or, it may, as shown, be provided with independent trolley frames Q and trolley wheels R. As shown, the cage 110 is connected to the frame of the trolley by connecting bar S.

The various motors are controlled from the operator's cage by any suitable type of controlling mechanism. As the specific means for controlling the motors do not form a part of the invention, except in the combination disclosed, such means are not illustrated in the accompanying drawing.

- The operation of this device is as follows. When a load is to be placed in the load supporting means, cables I are unwound from drums K by operating the motor L. When the cables have been lowered, the hooks H are secured to the load and the motor L is operated in a reversed direction to raise the load from the floor. The operator being in the cage M, operates motor P, and raises the cage. By operating the motor F, the forward trolley wheel D is revolved driving the trolley along track A.
- 10 The operator may raise and lower the cage at any time independent of the work supporting means by motor P. It is convenient for the operator to travel with the cage in the lowered position, and after the 15 work supporting means have been elevated, he may enter the cage and drive the machine by means of motor F without raising the cage. If it is necessary to raise the cage to avoid obstructions in the building, he may 20 do so while the trolley is in motion and independently of the work supporting means.
- 25
- 30

What I claim is:—

1. Conveying mechanism comprising a trolley adapted to travel upon an overhead track, work supporting means capable of vertical movement, a vertically movable operator's cage carried by the trolley and capable of independent vertical movement with respect to the work supporting means.

10 2. An overhead conveying mechanism, a trolley frame, trolley wheels carried by the frame, an overhead track, the trolley wheels being adapted to travel on said track, vertically movable work supporting means carried by the trolley frame, an operator's cage carried by the frame and capable of vertical movement independent of the work supporting means.

3. A construction in accordance with claim 1, wherein means are provided for controlling the elevation of the work supporting means, said controlling means being arranged in the operator's cage.

4. A construction in accordance with claim 1, wherein means are provided for controlling the elevation of the operator's cage, said controlling means being arranged in the operator's cage.

In testimony whereof, I affix my signature hereto.

H. M. LANE.
